(57) **CLAIM**

The ornamental design for a supporting post for panel, as shown and described.

DESCRIPTION

FIG. 1 is a perspective view of the top, front and right of a supporting post for panel showing my new design;

FIG. 2 is a front view thereof;

FIG. 3 is a rear view thereof;

FIG. 4 is a top plan view thereof;

FIG. 5 is an enlarged top plan view thereof;

FIG. 6 is a bottom view thereof;

FIG. 7 is a right side view thereof;

FIG. 8 is a left side view thereof;

FIG. 9 is an enlarged cross sectional view at a line 9-9 shown in FIG. 2;

FIG. 10 is an enlarged cross sectional view at a line 10-10 shown in FIG. 2;

FIG. 11 is an enlarged cross sectional view at a line 11-11 shown in FIG. 4;

FIG. 12 is a partially enlarged view of a portion 12 shown in FIG. 11;

FIG. 13 is a reference view of usage thereof; and,

FIG. 14 is a reference view of usage thereof.

The portions of the article in broken lines are shown for illustrative purposes only and form no part of the claimed design.
